UNITED STATES PATENT OFFICE.

GASTON STROBINO, OF PATERSON, NEW JERSEY.

PHONOGRAPH MACHINE.

Application filed October 29, 1920. Serial No. 420,374.

To all whom it may concern:

Be it known that I, GASTON STROBINO, a citizen of the United States, residing at Paterson, in the county of Passaic and State 5 of New Jersey, have invented certain new and useful Improvements in Phonograph Machines, of which the following is a specification.

This invention relates to phonograph and 10 the like machines (hereinafter termed phonograph machines), and it has for its principal object to provide an arrangement and construction of the system of parts that terminates in a needle or point to bear on the 15 record-forming surface that will conduct to such a transmission of vibrations that reproduction of sound in a materially improved degree will ensue and that will further make it possible for said system of parts to be 20 operative, when used in transmitting vibrations from such a surface, with record-grooves whose undulations are either vertical or lateral. The principal feature of my invention consists in a transmitter characterized 25 by an attenuated arm formed of thin material and having a thick vibratory head, and a record-groove-engaging needle or point fixedly connected to the thick head of said arm, the arm being movably connected 30 to a fixed part of the machine. I have herein shown two forms of a machine embodying this feature of my invention; the machine shown in Figures 1 to 6 embodies it with, and that shown in Figures 7 to 9 embodies it without, certain other novel features which when used with the principal feature of my invention increase the improvement which it represents in the way of better sound reproduction that is capable in 35 the use of the ordinary devices, and which have certain value quite independent of the principal feature.

In Figures 1 to 6, showing the first form,

Figure 1 is a front elevation, the case appearing in vertical section on line 1—1, Figure 2;

Figure 2 is a side elevation, the case again appearing in vertical section;

Figure 3 is a vertical front-to-rear section of the principal parts;

Figures 4 and 5 are side and end elevations of the record-groove-engaging end portion of the transmitter; and

Figure 6 is a diagrammatic view.

In Figures 7, 8 and 9, showing the other form,

Figure 7 is a front elevation, the case appearing in vertical section;

Figure 8 is an underneath plan of the part of the transmitter which includes the aforesaid attenuated arm and its thick head and the means to connect it to a fixed part of the machine; and

Figure 9 is a diagram illustrating this form.

Referring, first, to Figures 1 to 6:

In the upper compartment *a* of a suitable case *b* having a hinged cover *b'* is arranged the record-supporting platen *c* which is carried on the upper end of a shaft *d* which 70 protrudes upwardly through the horizontal partition *e* from the lower compartment *f* of the case and is adapted to be driven by any suitable motor in the latter compartment, such a motor being shown in Figure 2 and 75 designated *g*. The lower compartment may have a sound outlet means as *h* in one side, as the front, being preferably otherwise closed.

In the lower compartment is a rigid supporting arm *i*, projecting inwardly from its front wall. The end of this arm enters the loop *j* of a bracket *k* which is articulated to the arm by a pair of vertically opposed pivots *l* set in the bracket, one of which is 85 preferably a screw, as shown, to permit lost motion of the bearing formed to be taken up. The bracket is bifurcated at the top and one arm of its bifurcated portion is extended to form a segment *m* which is 90 surmounted by a plate *n* formed with a longitudinal slot *o*, said arm and the other arm *p* of the bracket carrying a pivot pin or bolt *q*, arranged horizontally, and on this is journaled a rocker *r* which has a long arm 95 formed with an abutment *t* to bear against the under side of plate *n*, the arm penetrating the slot *o* of said plate and being threaded thereabout and equipped with a nut *u* which may be made to coact with said abutment to 100 clamp the arm and hence the rocker to whatever position around pivot *q* they may be adjusted. A resilient support or connection surmounts the rocker, being preferably formed and arranged as follows: It is a 105 plate spring *v* which is rebent (there being preferably two distinct bends, *v'* and *v''*, the former somewhat acute and the latter ob-

tuse) and is secured by screws *w* passed through one arm (the arm adjoining the acute bend) with said arm bearing against the flat upper face *r'* of the rocker and so 5 that its arms project rearwardly.

Describing, now, the transmitter embodied in that form of the machine now being considered: There is a hollow membrane member *x*, preferably in the form of a truncated 10 cone and closed at its smaller end, which may be formed of some light, stiff sheet material, as parchment paper and preferably reinforced and stiffened at its margin by a hoop of wood or the like *y*; and there is a stylus 15 device consisting of a curved tubular stem or arm part *z*, a needle-carrying head to be described suitably fitted to one end of said stem, and a curved member 2 which is braced or otherwise secured to the other end of the 20 part or member *z* and forms therewith what substantially amounts to a fork, the members *z* and 2 being preferably formed of metal tubing and member 2 having its extremities beveled away so as to leave long blade-like 25 resilient extremities 2' which are secured fast to diametrically opposite points of the membrane member at or near its margin. It is desirable that the transmitter formed by the membrane member, the fork 30 *z*-2 and head should be rigid, i. e., unadapted to flex as an incident to the beveling or thinning down of the member 2 at the points 2-2'; the membrane member and the member 2 are both elastic elements, and it is further 35 desirable to utilize their elasticity in creating a state of tension in the transmitter. For these purposes, 3 designates take-up screws which are tapped into the member 2 and penetrate the reinforced margin of the membrane member, and 4 designates suitable 40 struts which traverse the marginal portion of the membrane member from points near the screws 3 to a substantially diametrically opposite point of the membrane member. 45 When the screws 3 are turned the transmitter comprising the fork *z*-2 and membrane member will obviously be set in a condition of tension. The transmitter has a 50 screw 5 set in the reinforced marginal portion of the membrane member thereof at a point adjoining and opposite the juncture between the members *z* and 2, and this screw is tapped into the upper arm of the spring support or connection *v*, so that the said 55 transmitter hangs pendent from said arm, the connection (said screw) between the transmitter and arm being an inflexible one. It will be seen (particularly on a view to the diagram, Figure 6) that the structure comprising the transmitter, screw 5, spring support *v* and rocker *r* are carried on arm *i* through the medium of a universal-joint connection whose axes *g* and *l* permit up and down movement of said structure, as in 60 65 changing records, and horizontal movement.

thereof, in order that the needle may progress generally radially of the record A when the machine is operating. In order to relieve the record of some of the pressure that would otherwise be incident to the weight 70 of the transmitter—in short, in order to adjust the pressure of the needle on the record—arm *s* may be shifted and then secured in the new position by means of nut *u*. So far as I am aware it is broadly new in phonograph machines to arrange a transmitter, including a membrane or other vibratory member arranged lower than the platen and an upwardly and laterally projecting portion terminating in a stylus device, so that 75 its stylus device will overhang and rest on the record, the transmitter being suitably supported in operative movable relation to the platen. It is also new to provide a carrier member, as *k*, movable in a plane parallel 80 with the record surface and a transmitter-including structure, as *i*, *v*, *y*—*x*, *z* attached to the carrier and having a terminal (as a needle or point, to be described) to rest 85 on the record and being flexible and elastic 90 between the carrier and terminal, and further provide said structure and the carrier with coacting means to secure said structure, when the point device rests on the record, in different degrees of tension. The membrane 95 member occupies, as shown, the lower compartment of the case—the stylus device protruding up through a hole 6 in partition *e*—and so is out of the way and obscured. The hereinbefore mentioned head of the transmitter, generally denoted by *B*, is in the present case made in two parts 8 and 10, one to receive the needle or point *C* and the other having a plug to fit into tube *z*, parts 8 and 10 being connected by a coupling 9 fixed in 105 part 10 but affording a pivotal support—the axis 8' being horizontal—to part 8, so that there will be a vertical yield, which is resisted by a spring 11. The needle or point *C* is shown as a fork with a threaded stem 110 7 to fit into head *B* and a head 7' having (here) three arms 7'', one to receive a plain needle proper (shown in axial alinement with stem 7) for laterally or vertically cut record-grooves and the other two to receive 115 respectively, Edison and Pathé needles proper for V-shaped and U-shaped record grooves, respectively. In changing from one to another kind of record the operator has only to turn fork 7 on its stem as an axis to 120 bring the appropriate needle proper into operative relation to the record-groove; when either of the Edison or Pathé needles proper is in use the fork stands in a vertical plane; when the plain needle proper is in use the 125 fork is shifted on its axis through 90°.

The pivot 8' permits the part 8 of the transmitter head which actually carries the point-device or needle to yield vertically relatively to the remainder of the trans- 130

mitter. The yield thus afforded serves to absorb the shock which, on account of the weight and inertia of the transmitter, the record would undergo, with consequent injury, when the record is of the lateral-cut type, where the point device seeks to follow a direct course and "short-cuts" the deflections of the record-groove and so undulates up and down somewhat. So far as I am aware it is broadly new to mount a point-device in a part of a transmitter yieldable up and down relatively to the remainder.

Referring now, to Figures 7 to 9:

Parts *a*, *b*, *b'*, *c*, *d*, *e*, *f*, *g*, *h* and *A* are or may be the same as parts *a* to *h* and *A* heretofore described, except that compartment *f* is here shallower than in the first form. The transmitter parts *z'*, *B'* and *C'* are also essentially the same as the parts *z* and *B* and *C* described, except that needle *C'* is fixedly connected to a plate spring *C''* which is in turn fixedly connected to the head. A block 12 is fitted to the outer end of tube *z'* and it is equipped with a downwardly protruding bearing pin 13 whose upper end forms a conical bearing socket 14 for the tapered lower end of a bearing pin 15 which seats in said socket; a slot 16 in the block, extending longitudinally thereof and but just wide enough to admit pin 15, allows the latter to oscillate longitudinally but not transversely of the block. The lower end of pin 13 and upper end of pin 15 are also tapered, being received in suitable bearings formed in the opposite portions of a rebent bracket 17 which overhangs a recess 17' in and has one arm suitably fixed to part *e'* of wall *e*. The structure *B'*, *z'* 12 can swing on the axis 13—15 horizontally, or over the face of the record, and the connection is also such that it can be swung up in a vertical plane but cannot fall over sidewise, due to the slot 16 confining pin 15 to a plane of articulation longitudinal of said structure. A spring 18 holds pin 15 with its upper end always engaged in its bearing in bracket 16. In order to adjust the bearings of the pins 13—15 in the bracket the latter is traversed by a stem 19 which is fixed in one arm and penetrates the other arm of said bracket and has an adjusting nut 20 screwed thereon and bearing against the latter arm, it being desirable to avoid any tendency of pin 15 to rattle.

The transmitters shown in both forms of the machine are essentially the same in that each is characterized by an attenuated arm *z* (or *z'*) formed of thin material and having a thick vibratory head *B* (or *B'*), and a record-groove-engaging needle or point fixedly connected to the thick head of said arm, the arm being movably connected to a fixed part of the machine. Since sound reproduction is not by my transmit-

ter dependent on flexion, as of a diaphragm 65 in the case of the ordinary transmitter (which diaphragm is substantially inoperative unless set in a certain relation to the undulations of the record groove), but is the result of vibrations acting from point 70 or needle *C* through the substance of the thick head *B* in every direction, the transmitter is not only adapted to both vertically and laterally cut records, interchangeably, but the sound reproductions are much more 75 in faithful accord with the original. I utilize this quality of a thick vibratory body to best advantage in a practical organization of parts by making it a head on the end of an attenuated supporting portion 80 formed of thin material (thin, so that the vibrations do not expend themselves in solid matter, as they in large measure would if said portion were as thick as or thicker than the head) and arranged and operating as 85 set forth. The tube *z* is preferably made of resonant material and so serves as a good means itself for setting up sound waves in the atmosphere, as well as to conduct the vibrations created in the head to an amplifier, as the means *2*, *x* *y* of Figures 1 to 6, or the sound-box formed by the (wooden) walls of chamber *f* in Figure 7. For the material of the head I use any resonant substance, having used with good results such non-metals as wood, fibre or the composition of which phonograph records are usually made; tube *z* is preferably metal, as brass.

Having thus fully described my invention, what I claim as new and desire to secure by Letters Patent is:—

1. In combination, a stationary supporting means, a movable record supporting platen therein, and a transmitter including an attenuated arm formed of thin material 105 and having a thick vibratory head, and a record-groove-engaging point device fixedly connected to the thick head of said arm, said arm being movably connected to said supporting means at a point remote from the head and holding the head and point device in operative relation to a record on the platen and the transmitter being out of contact with said supporting means between said point and the point of contact of the 110 point device with the record.

2. In combination, a stationary supporting means, a movable record supporting platen therein, and a transmitter including an attenuated arm formed of thin resonant 120 material and having a thick vibratory head, and a record-groove-engaging point device fixedly connected to the thick head of said arm, said arm being movably connected to said supporting means at a point remote from the head and holding the head and point device in operative relation to a record on the platen and the transmitter being out 125

of contact with said supporting means between said point and the point of contact of the point device with the record.

3. In combination, a stationary supporting means, a movable record supporting platen therein, and a transmitter including an attenuated arm formed of thin tubular material and having a thick vibratory head, and a record-groove-engaging point device 10 fixedly connected to the thick head of said arm, said arm being movably connected to said supporting means at a point remote from the head and holding the head and point device in operative relation to a record 15 on the platen and the transmitter being out of contact with said supporting means between said point and the point of contact of the point device with the record.

4. In combination, a supporting means, a 20 movable record-supporting platen therein, and a transmitter including a vibratory member arranged under the platen and an upwardly and laterally extending portion terminating in a record-groove-engaging 25 point device overhanging a record placed on the platen, said means supporting the transmitter in operative movable relation to a record on the platen.

5. In combination, a supporting means, a 30 movable record-supporting platen therein, and a transmitter including a vibratory member arranged lower than the platen and an upwardly and laterally extending portion terminating in a record-groove-engaging 35 point device and overhanging a record placed on the platen, said means having a pivotal joint device to support the transmitter in operative movable relation to the platen.

6. In combination, a supporting means, a 40 movable record-supporting platen therein, a carrier member in said means, and a transmitter-including structure attached to the carrier member and having a record-groove- 45 engaging point device and being flexible and elastic between said device and its point of attachment to the carrier member, said structure and the carrier having coacting means to secure said structure, when the 50 point device rests on the record, in different degrees of tension.

7. In combination, a supporting means, a 55 movable record-supporting platen therein, a carrier member in said means, and a transmitter-including structure pivoted to the carrier member on an axis substantially parallel with the record surface and having a record-groove-engaging point device and being flexible and elastic between said point 60 device and axis, whereby the tension of said structure may be varied when the part of said structure adjacent said axis is shifted on said axis while the point device bears on the record, said structure and carrier having

co-acting means to hold said part in the position to which it is thus shifted. 65

8. In combination, a supporting means, a movable record-supporting platen therein, and a transmitter including a vibratory laterally reaching structure and a stylus device projecting upwardly from one end of and then reaching laterally over and in substantially the same direction as said structure, said supporting means having means, 70 connected with the transmitter to movably support said transmitter with the stylus device resting on a record on the platen. 75

9. In combination, a supporting means, a movable record-supporting platen therein, a transmitter including a hollow vibratory 80 member opening laterally, and a stylus device projecting from said member and adapted to bear on the record, a part of said supporting means projecting into said member, and means to connect said transmitter 85 to said part.

10. A phonograph transmitter structure including a stiff membrane member and a stylus device including a bent elastic portion, said member and stylus device holding 90 each other in a state of tension.

11. A phonograph transmitter including a stiff hollow membrane member, a stylus device including a bent elastic portion extending around the membrane member, and 95 means, connecting said member and device, to cause each to hold the other in a state of tension.

12. A phonograph transmitter including a stiff membrane member, a stylus device including a bent elastic portion extending 100 around, and attached at spaced points thereof to, the membrane member and spaced therefrom between said points, and means to draw together the stylus device and member 105 having connection with them between said points.

13. A phonograph transmitter including a stiff membrane member, a stylus device including a bent elastic portion extending 110 around, and attached at spaced points thereof to, the membrane member and spaced therefrom between said points, means to draw together the stylus device and member having connection with them between said 115 points, and strut means connecting one side of the membrane member near the first means with the opposite side of said member.

14. A phonograph transmitter including a 120 stylus device having a bent elastic portion and means to hold said bent elastic portion in a state of tension including a membrane member around which said portion extends and secured to said portion at spaced points 125 thereof.

In testimony whereof I affix my signature.
GASTON STROBINO.
